TUBULAR POST

Josef Pfistershammer, Zurich, Switzerland

Application July 16, 1935, Serial No. 31,954
In the Netherlands July 26, 1934

6 Claims. (Cl. 189—26)

This invention relates to a tubular post tapering towards the upper end and with supporting arms for the electric wires on the upper portion of the post.

5 The invention consists particularly in the simple construction and fitting together of the post when erecting, the post being composed of a plurality of tubular sections and the supporting arms equipped with sleeves fitting on the 10 uppermost section of the post, and all the tubular sections of the post and the supporting arms with their sleeves being fitted and clamped together in a simple manner.

The invention likewise consists in the construction and fitting together of the post in such a manner that the interior of the post is ventilated and moisture condensing on the inner side of the wall of the post can drain off to the outer side thereof.

20 Several embodiments of the invention are illustrated by way of example in the accompanying drawing in which:—

Fig. 1 shows the upper portion of a post in longitudinal section.

25 Fig. 2 is a similar view of a post of modified construction.

Fig. 3 shows a third form of construction in elevation.

30 Figs. 4 and 5 are cross-sections on lines IV—IV and V—V of Fig. 1.

Fig. 6 is a cross-section on line VI—VI of Fig. 1 and shows a modification of the post in Fig. 1.

35 Figs. 7 and 8 are cross-sections on lines VII—VII and VIII—VIII of Fig. 2.

Figs. 9 and 10 are cross-sections on lines IX—IX and X—X of Fig. 3.

The tubular sections of the post according to the invention are made of sheet steel 0.8 to 2.5 mm in thickness, the lowermost section having 40 the thickest and the uppermost the thinnest wall thickness. The tubular sections are about 2 metres in length and, to protect them against turning are of oval or elliptical cross-section; and in a certain form of construction may be of 45 circular cross-section. They taper gradually from their lower end to their upper end so that the wider lower end of each tubular section of the post fits over a short length of the narrower upper end of the preceding tubular section.

50 The lower part of every section fits very accurately upon the upper part of the preceding section. The wall thickness of the sections is very thin, the circumference of the sections is very great relative to the wall thickness. The ends of 55 the sections are therefore yieldable and elastic

so that their elliptic edge might be deformed by the hands. If, however, one section is placed with its lower part upon the upper part of the preceding section and strongly pressed down, the telescoped parts of the sections come into such 5 intimate contact that the sections can no longer be mutually turned and also not separated the one from the other without separate auxiliary means. No connecting means are therefore required to protect the telescoped sections against 10 turning and getting loose.

The lower ends of the sections, owing to their yieldability, can even be clamped over unevennesses, and projections on the upper ends of the preceding sections and thus enable longitudinal 15 channels to be formed between the clamping surfaces of the superposed portions of the sections, through which channels air circulates between the interior of the post and the atmosphere and moisture condensing on the inner surface of the post can run out through these channels. The same 20 advantage is attained when the tubular sections are lap-welded. The lower edges of the sections can easily be stretched over the overlapping edges at the upper ends of the preceding sections. The supporting arms for the electric wires are 25 clamped and stretched over the upper most tubular section in a similar manner as every supporting arm is arranged on an elliptical sleeve tapering towards its upper end, the internal circumference of said sleeve being fitted and clamped at a certain point on the uppermost tubular section. These sleeves can likewise be clamped over 30 projections on the tubular section, so that channels are formed between the clamping surfaces, through which channels any water which penetrates between the clamping surfaces can flow 35 off.

All the forms of construction illustrated have 40 for their object to enable the post and the supporting arms for the electric wires to be made and erected in the simple manner described, to form air channels between the clamping surfaces at the joints and to make all joints secure against turning and working loose.

45 Fig. 1 shows the upper four tubular sections 1, 2, 3, 4 of a post with two sleeves 5 and 6 clamped on the uppermost section 1 and carrying supporting arms 7 and 8 for electric wires. The post is covered at its upper end by means of a cap, the side wall of which, as shown in Figs. 2 and 3, may be provided with grooves to allow air to escape from the interior of the post. The wide lower ends of the tubular sections 1, 2, 3 and so on are each slipped over the narrower 50 55

upper ends of the preceding sections **2**, **3**, **4** respectively and adapted to be pressed the one over the other along a short length. Particularly the lower end of each tubular section is yieldable owing to the thinness of the sheet steel employed, which is only 0.8 to at the most 2.5 mms thick, so that the two section ends fitted the one over the other are clamped tightly together. The sleeves **5** and **6** carrying the supporting arms **7** and **8** respectively, like the tubular sections, are of oval or elliptical cross section and taper corresponding to the upper section **1** so that their internal circumference corresponds with the outer circumference at certain points **15** of the upper section **1**. These points on the upper section **1** are determined by the distances for which the supporting arms **7** and **8** are to be spaced in vertical direction. The sheet metal from which these sleeves are made is as thin **20** as that of the uppermost tubular section so that these short sleeves are also yieldable along their entire length and can consequently be tightly clamped on the section **1**. The sections **1**, **2**, **3**, **4** and also the sleeves **5**, **6** are butt-welded at their **25** seam. The clamping surfaces at the individual fitting points of the sections and sleeves may under certain circumstances bear tightly on one another so as to form air and water-tight joints. It is, however, preferable to make the interior **30** of the post communicating with the atmosphere and especially to lead off the moisture which condenses, runs down the outer side of the walls of the sections, collects on the upper edges of the sections on to which they are fitted, and in the **35** course of time penetrates between the clamping surfaces. The water which runs down the outer side of the uppermost tubular section also collects on the upper edges of the sleeves **5**, **6** and in the course of time penetrates between **40** the clamping surfaces of the section and sleeves. Fig. 6 shows how the water can be conducted off in a construction when the sections and sleeves are made with butt-welded seams. One or several rods **9** are inserted between the clamping **45** surfaces and the walls of the portion of the next following tube to be fitted is stretched over these inserts. The inserts are preferably fitted on the two longer sides of the oval cross-section and they may be formed by a wire or strip of sheet metal provided with a hook which is hooked over the upper edge of the tubular section before the **50** next following tubular section is fitted. In a similar manner such inserts may be hung in the sleeves **5**, **6**. As shown in Fig. 6 gaps **10** are formed adjacent these inserts **9** between the clamping surfaces, through which gaps water condensed on the interior of the post can drain off between the clamping surfaces of two sections and rain water which has penetrated **55** between the upper section and the sleeve can flow off.

In the modified form of construction illustrated in Fig. 2 the tubular sections **11**, **12**, **13**, **14** have lap-welded seams. The overlap is situated **60** on one of the wide sides of each tubular section and the sections are fitted together so that the overlap seams of neighbouring tubular sections are on opposite sides of the post. The tubular sections, owing to the yieldability of their ends, **65** can be stretched over the overlap edges, but a gap **20** or **20'** is formed between the clamping surfaces, beside the outer overlap edge **19** of the inner section end and beside the inner overlap edge **19'** of the outer section end, through which **70** gap the water of condensation can flow off (Fig. **75**

7). The sleeves **15**, **16** with the supporting arms **17**, **18** may have butt-welded seams, as in Fig. 1, and in this instance a longitudinal channel is then formed between the clamping surfaces along the outer overlap edge of the upper tubular **5** section **11**. Or the sleeves may also be lap-welded like the tubular sections so that at the overlap edge **19** of the tubular section **11** and at the overlap edges **19'** of the sleeves, channels **20** or **20'** respectively are formed through which the **10** water can drain off from the clamping point.

In the modification shown in Fig. 3 the tubular sections **21**, **22**, **23**, **24** of the post are each composed of two long pieces which are united by two lap-welded longitudinal seams. The seams **15** **29** extend obliquely along the tubular sections and are all parallel in all the tubular sections. When the ends of the tubular sections are clamped the one on the other, the outer overlap edge of the inner tubular section and the inner **20** overlap edge of the outer tubular section come together at each clamping point. Between these joining overlap edges a narrow gap **30** is formed and serves as draining channel between the **25** clamping surfaces. The sleeves **25**, **26** on which the supporting arms **27**, **28** are welded may be made in a similar manner like the tubular sections **21**, **22**, or they may have only a butt-welded **30** seam, as shown in Fig. 1. In both instances draining channels are formed owing to the lap-welding of the seams of the uppermost tubular section **21**.

It is evident that in this form of construction the overlap edges of the inner and outer tubular sections meeting at the joints give an additional **35** security against turning of the tubular sections and that consequently, in this construction, the tubular sections need not be of oval cross-section, but may be of circular cross-section. This form of construction is therefore applicable also for **40** posts composed of cylindrical tubular sections which taper gradually towards the upper ends.

The post can be fitted together lying on the ground and erected in finished condition. When climbing the post by means of climbing irons, **45** the individual tubular sections and the sleeves of the supporting arms are pressed and clamped tightly one in the other by the weight of the workman climbing the post. The tubular sections for the upper post, owing to their light **50** weight, can easily be carried up and fitted by the workman climbing the post.

Owing to the tubular sections and also the sleeves of the supporting arms being tightly **55** clamped together, it is scarcely possible for the tubular sections and for the supporting arms to turn mutually. Such a turning is further rendered impossible by the oval cross-sectioned shape of the tubular sections and sleeves and by the inserts or overlap edges forming the draining channels, and, in the arrangement according to Fig. 3, the abutting overlap edges also form an abutment which prevents mutual turning of the post sections.

I claim:—

1. A tubular post, comprising in combination a plurality of tubular sections tapering towards the upper end and made of sheet steel of such thin thickness that the ends of the sections are yieldable and spreadable, the wide lower end of **70** each tubular section slipped over a length of the narrow upper end of the preceding section, all said sections being of elliptic cross-section to prevent mutual turning, supporting arms for electric wires each having a sleeve tapering towards its **75**

upper end and made of thin sheet steel so that it is yieldable and spreadable along its entire length, said sleeves adapted to be slipped over the narrow upper end of the upper tubular section of the post and having an elliptic cross section corresponding with the elliptic cross section of said upper tubular section to prevent mutual turning.

2. A tubular post, comprising in combination a plurality of tubular sections tapering towards the upper end and made of pieces of sheet steel with lap-welded seams, the sheet steel being so thin that the ends of the tubular sections are yieldable and spreadable, the wide lower end of each tubular section adapted to clamp on a short length of the narrow upper end of the preceding tubular section, the edges of the overlap seams forming channels between the clamping surfaces at the joints between the fitted tubular sections, supporting arms for electric wires each having an oval sleeve at the inner end, said sleeve tapering in upward direction and being made of thin sheet steel so that it is yieldable and spreadable along its entire length, said sleeves adapted to be slipped over the narrow upper end of the upper tubular section of the post and having an internal circumference corresponding to the outer circumference of the uppermost tubular section at a predetermined point of its height and adapted to clamp on the upper tubular section each one at its predetermined point.

3. A tubular post, comprising in combination a plurality of tubular sections tapering gradually in upward direction and of oval cross-section, said tubular sections being made of sheet steel with lap-welded seams and so thin that the ends of the tubular sections are yieldable and spreadable each tubular section adapted to clamp with its wide lower end over a short length of the narrower upper end of the preceding tubular section, and to stretch the overlap seam edges, supporting arms for electric wires, a tapered sleeve of oval cross section at the inner end of each supporting arm, each sleeve made of sheet steel with lap-welded seam and of such slight thickness that the seams are yieldable and spreadable, the internal circumference of said sleeves corresponding with the external circumference at a certain point of the upper tubular section of the post and adapted to clamp on to these points of the upper tubular section and to spread over the overlap edge of this tubular section.

4. A tubular post, comprising in combination a plurality of tubular sections tapering gradually in upward direction and of oval cross-section, each of said tubular sections composed of two pieces of sheet steel with opposite lap-welded seams and so thin that the ends of the sections are elastic and expandable, the lower wide end of each tubular section being clamped on the narrow upper end of the preceding tubular section, and the overlap welded seams of the two parts of each tubular section extending obliquely in the tubular sections and the seams of all tubular sections parallel to one another, and the tubular sections fitted together so that at the joints between two tubular sections the inner overlap edge of the outer tubular section and the outer overlap edge of the preceding tubular section meet and form an abutment to prevent mutual turning of the tubular sections, a gap being formed between the two meeting overlap edges forming a channel between the clamping surfaces at the clamping

point, supporting arms for electric wires each having an oval sleeve at the inner end of said sleeve tapering in upward direction and being made of thin sheet steel so that it is yieldable and spreadable along its entire length, said sleeves adapted to be slipped over the narrow upper end of the upper tubular section of the post and having an internal circumference corresponding to the outer circumference of the uppermost tubular section at a predetermined point of its height and adapted to clamp on the upper tubular section each one at its predetermined point.

5. A tubular post, comprising in combination a plurality of tubular sections tapering gradually in upward direction and of oval cross-section, each of said tubular sections composed of two pieces of sheet steel with opposite lap-welded seams and so thin that the ends of the sections are elastic and expandable, the lower wide end of each tubular section being clamped on the narrow upper end of the preceding tubular section, and the overlap welded seams of the two parts of each tubular section extending obliquely in the tubular sections and the seams of all tubular sections parallel to one another, and the tubular sections fitted together so that at the joints between two tubular sections the inner overlap edge of the outer tubular section and the outer overlap edge of the preceding tubular section meet, supporting arms for electric wires, a tapered sleeve of oval cross section at the inner end of each supporting arm each sleeve formed of two pieces of sheet steel with two opposite lap-welded seams and so thin that the pieces are elastic, the internal circumference of said sleeves corresponding with the outer circumference of a certain point of the uppermost tubular section of the post, the sleeves clamped on to the uppermost tubular section of the post and stretched over the overlap edges thereof at the predetermined point, the overlap edges of the sleeves being obliquely directed and parallel to those of the uppermost tubular section and the sleeves being so clamped on this tubular section that the inner overlap edges of the sleeves meet the outer overlap edges of the uppermost tubular section, a gap being formed between the meeting overlap edges and forming a channel between the clamping surface of said sleeves and of said uppermost tubular section.

6. A tubular post, comprising in combination a plurality of conical tubular sections, each section composed of two pieces of sheet steel of semi-circular cross-section and with two mutually opposite lap-welded seams, and the sheet steel being so thin that the ends of the sections are elastic, the wide lower end of each section clamped on to a short length of the narrow upper end of the preceding tubular section and fitted so that the inner overlap edges of the outer tubular section are opposite the outer overlap edges of the preceding tubular section and form an abutment against turning of the tubular sections, supporting arms for electric wires, a tapered sleeve of thin pliable sheet steel at the inner end of each supporting arm, the internal surface of each sleeve corresponding to the external surface of the uppermost tubular section of the post at a certain point of said tubular section, each sleeve clamped on the point of said uppermost tubular section and stretched over the overlap edges thereof at this point.
